UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF AND APPARATUS FOR FORMING HEELS.

Application filed July 25, 1918, Serial No. 246,628. Renewed October 24, 1922. Serial No. 596,671.

To all whom it may concern:

Be it known that I, ERASTUS E. WINKLEY, a citizen of the United States, residing at Lynn, in the county of Essex and State of Massachusetts, have invented certain new and useful Improvements in Methods of and Apparatus for Forming Heels; and I do hereby declare the following to be a full, clear, and exact description of the invention, 10 such as will enable others skilled in the art to which it appertains to make and use the same.

This invention relates to the manufacture of boot and shoe heels comprising a 15 plurality of superposed lifts, and it has special reference to heel assembling devices and methods employed in connection therewith for assembling and definitely aligning and positioning the component lifts thereof 20 to form a heel of a particular shape.

In Letters Patent No. 123,736, granted Feb. 13, 1872, to Shaw, there is disclosed a boot or shoe having a two part bottom comprising a short outsole and a recessed 25 heel embodying a plurality of normal sized lifts and a relatively short base-lift so positioned with respect thereto as to provide a rabbet extending transversely across the breast end of the heel-seat to receive the 30 shank-end of the short outsole.

In order to economically manufacture such recessed heels of high grade, it is desirable that the component lifts thereof shall be accurately aligned and positioned both 35 laterally and with relation to their breast edges before being compressed and consolidated in the usual heel compressor. Such a heel is thus adapted to closely fit throughout its entire surface within the mold of the 40 heel compressor, whereby the pressure to which it is subjected is equally distributed throughout the heel and results in a uniformly consolidated product of superior quality.

Accordingly, it is one of the primary objects of this invention to provide a simple, effective and reliable assembling device for producing an accurately aligned multi-lift heel comprising a short base-lift, the breast 50 edge of which is indented from the breast surface of the heel to form a rabbet extending transversely across the breast end of the heel-seat.

A further object of the invention is to 55 provide a simple and expeditious method

of assembling and aligning the component lifts of a heel to produce a heel having the above indicated characteristics.

So far as the broad features of the invention are concerned, it is obviously immaterial whether the lifts be definitely positioned or aligned one at a time or concurrently, since the apparatus permits either mode of assembling the heel with accurate results. 60

Other objects of the invention and features by means of which they are attained will become apparent from the following description of the preferred embodiment of the invention illustrated in the accompanying 65 drawings, in which Figure 1 is a side elevation of the device, a small portion thereof being broken away for clearness of illustration; Fig. 2 is a top plan view with the aligning device in position; Fig. 3 is a 70 right hand end elevation; and Fig. 4 is a view similar to Fig. 1, showing the base lift in its final position.

In the embodiment of the invention illustrated in the drawings the bed plate 2 has an 75 upwardly projecting portion 4 adapted to support a fixed upright plate 6. Resting upon the bed plate opposite the plate 6 is a block 8 fixed to a rod 10 slidably mounted in a bearing 12 so that the block is movable 80 toward and away from the plate 6. Secured to the bed plate at each side of the plate 6 and the block 8 are guide bars 14. The plate 6, the block 8, the guide bars and the bed plate form respectively the four sides 85 and the bottom of a heel holding form 90 adapted to receive the lifts 16 with their breasts aligned against the bed plate. The guide bars serve as lateral edge guides for the lifts and are beveled, as shown in Figs. 95 2 and 3, so as to facilitate the placing of the lifts therebetween, and they also diverge from the plate 6 to accommodate the pitch of the heel pile. The guide bars, as shown, 100 may be secured to the bed plate with provision for adjustment thereon toward and away from each other and angularly to adapt them for use in connection with heel piles of varying sizes and styles. Means, in addition to the breast gage 2 is provided 105 for insuring accurate alignment of the breast edges of the lifts, comprising an arm 18 which is pivoted at 20 between ears 22 rising from the bed plate and which is provided with an inclined lift engaging sur- 110

face 24 and a handle 26. This arm 18 normally occupies an inoperative position against a stop 28, as indicated in Fig. 1, but is adapted to be swung downwardly into the position shown in Fig. 4, so as to bring the inclined surface 24 into engagement with the rear edges of the lifts and press the lifts downwardly, if necessary, until their breast edges rest squarely upon the bed plate. All of the lifts except the short base-lift may be thus correctly positioned relative to each other by the means above described.

The means for positioning the base-lift comprises a bifurcated bell crank lever 30 fulcrumed at 32 on opposite sides of the block 8. The upwardly extending arms of the lever 30 unite above the block 8 and terminate in a handle 34. The free arms 36 of the lever project into grooves 38 formed in the bed plate and extend beyond the block 8 and into the heel form a sufficient distance to enable them to function as a breast gage for the base-lift when swung upwardly. Normally, the free arms 36 lie in the grooves 38 and just below the top surface of the bed plate, so that they will not interfere with the preliminary positioning of the lifts if the heel is introduced as a whole. The handle 34 may be swung to the right, from the position shown in Fig. 1, causing the arms 36 to raise the base-lift, by an engagement with its breast, to a position against the arm 18, as shown in Fig. 4.

The device is used in the following manner. It is preferred to have the lifts, which are of different sizes, assembled in proper order preparatory to being operated upon by the device, and delivered in separated piles by any convenient and suitable means to a receiving table within reach of the operator. Each pile will have assembled therewith at its heel-seat end a short base-lift of the kind shown in the drawings. As each pile is placed in the holding device the guide bars 14 cause the lifts to be correctly positioned laterally relatively to each other. By pressing the arm 18 downwardly against the upwardly projecting rear edges of the lifts, those which are out of alignment are pushed downwardly and the breast edges of all the lifts are squarely and accurately aligned against the breast gage 2. The short base-lift drops by gravity against the bed plate when the lever 30 is in its forward position (see Fig. 1) and, therefore, is not engaged and positioned with relation to the others by the arm 18. Since the base-lift lies in the path of the upward movement of the bell crank arms 36, the movement of the handle 34 to swing these arms upwardly will cause the base-lift to be raised until its rear edge engages the inclined surface 24 on the arm 18, when it will be positioned correctly with relation to the other lifts. The breast edge of the base-lift will thus be accurately in-

dented a predetermined amount relatively to the breast edges of the other lifts so as to form a rabbet adapted to receive the shank end of a short outsole. The final form of the breast of the heel is thus determined by the bed plate 2 and lever arms 36 forming together a complete breast gage for the type of heel being produced.

When all the lifts have been thus accurately aligned, pressure is applied to the block 8 through the rod 10 by any suitable means, not shown in the drawing, so as to hold the lifts firmly while they are being secured together by the driving of a nail through the pile from the top-lift to base-lift. As shown in Fig. 1, the plate 6 carries a nail throat 40 which extends between the ears 22 parallel to the bed plate through which nails may be driven into the heel pile by a nail driver shown in Fig. 1 at 42. The driver may be operated by any usual or suitable means.

While the drawings illustrate the invention as embodied in a device adapted to receive the lifts in upright position upon a horizontal support, it is to be understood that this arrangement of the apparatus is not essential. Furthermore, while, as stated, it is preferred to introduce the component lifts of the heel-pile into the holding device as a unit, it is within the scope of the invention to introduce the lifts or other component parts of the heel singly, that is, to build the heel in the holding device, as is now the customary heel building practice.

While, for illustrative purposes the invention is set forth in connection with a form of assembling or heel-lift positioning device embodying specific structural details, arrangement and location of parts and mode of operation, it should be understood that, broadly considered, this special type of apparatus is merely exemplary of one of many forms of devices constructed and operated in accordance with the invention, and that many and material modifications may be made therein without departing from the spirit and scope of the invention.

What is claimed as new is:—

1. A heel-lift positioning device comprising means for holding a pile of lifts with their breast edges in alignment, and means for displacing one of said lifts to set its breast edge back from the plane of the breast edges of the other lifts without destroying the stacked relationship of the lifts.

2. A heel-lift positioning device comprising a heel form having a support for the breast edges of a pile of lifts, means for maintaining said lifts in stacked relation; and means for displacing one of said lifts rearwardly with relation to the other lifts of the pile.

3. A heel-lift positioning device having, in combination, a support for the breast

edges of a pile of lifts, means for supporting the end lifts, edge guides for positioning the lifts laterally, and means for displacing one of said lifts rearwardly with 5 relation to the other lifts of the pile.

4. A heel-lift positioning device having, in combination, a bottom support for the breast edges of a pile of lifts assembled in proper order to form a heel, means for supporting the ends of said pile, means normally engaging the base lift and adapted to be actuated to raise said base lift relatively to the others, and means for preventing the other lifts from being moved by the raising 10 of said base lift.

5. A heel-lift positioning device for holding a pile of lifts including a comparatively short base lift in stacked relation, having, in combination, an aligning surface opposite the breast edges of said lifts, a movable member adapted to be placed in position to engage the rear edges of all of the lifts except the base lift and bring their breast edges into alignment against said surface, 20 and means for moving said base lift into engagement with said positioning member to position it with its breast edge set back from the breast edges of the other lifts.

6. A heel-lift positioning device, comprising a heel form for receiving a heel pile composed of a plurality of lifts of normal size and a short base lift, and means associated with said form for aligning the breasts of said normal lifts and positioning said 35 short base lift at the rear of the lift next adjacent to it.

7. A heel-lift positioning device having, in combination, a bed plate for supporting the breast edges of a plurality of lifts assembled in a heel pile, means for supporting the end lifts, lifting means for raising the base lift relatively to the others, and a member adapted to hold the other lifts firmly against said bed plate while said base lift is 45 being raised and to limit the upward movement of the base lift.

8. A heel-lift positioning device having, in combination, a bottom supporting plate for the breast edges of a stack of lifts including a comparatively short base lift, means for holding the lifts in stacked relation, means for positioning the lifts laterally, a positioning member adapted to engage the rear edges of all the lifts except 50 the base lift, to press said lifts toward said bottom supporting plate so as to aid in positioning them, means for engaging the base lift and moving it into contact with said positioning member so as to bring its rear edge into correct position relatively to the rear edges of the other lifts, and means for securing the lifts together.

9. The method of forming heels which consists in stacking together a plurality of lifts with their breast edges in alignment,

and subsequently without destroying the stacked relation of the lifts displacing one of the end lifts so that its breast edge is set back from the plane of the breast edges of the other lifts.

10. The method of forming heels which consists in stacking a plurality of lifts with their breast edges in alignment including a comparatively short base lift, and in subsequently displacing said base lift rearwardly to set its breast edge out of alignment with the breast edges of the other lifts.

11. The method of forming heels which consists in assembling a plurality of lifts in stacked relation with their breast edges aligned, said lifts having associated therewith a short base lift, thereafter positioning said base lift at the rear of the lift next adjacent it forming a rabbet at the breast of the heel-seat, and finally securing all the 80 lifts together.

12. A heel assembling device having, in combination, means for holding in stacked relation the component lifts of a heel including a short base-lift, and breast gaging 90 means constructed and arranged to align the breast edges of the normal lifts and position the short base lift with its breast edge indented relatively to the breast formed by the aligned normal lifts.

13. A heel assembling device having, in combination, means for holding in stacked relation the component lifts of a heel including a short base-lift, separate gaging members for the breast edges of the normal 100 lifts and of the short base-lift, and means co-operating therewith to align said lifts with the breast edge of the base-lift indented relatively to the breast edges of the normal lifts.

14. A heel assembling device having, in combination, means for holding in stacked relation the component lifts of a heel including a short base-lift, and a plurality of relatively movable members for severally 110 engaging the breast and rear edges of each lift for definitely positioning each lift so that the breast edges of all of the normal lifts are in alignment and the breast edge of the short base-lift is indented from the 115 breast edges of the aligned normal lifts.

15. A heel assembling device having, in combination, means for engaging the end faces of the component lifts of a heel including a short base-lift to hold them in 120 stacked relation, and gaging means against which the breast edges of all of the lifts are positioned to align the breast edges of the normal lifts and to definitely locate the short base-lift with its breast edge indented 125 from those of the aligned normal lifts.

16. A heel assembling device having, in combination, means for holding in stacked relation the component lifts of a heel including a short base-lift, gaging means against 130

which the breast edges of the lifts engage constructed and arranged to indent the base lift with respect to the normal lifts, and means for actuating each one of said lifts to effect its full engagement with said gaging means.

17. A heel assembling device having, in combination, means for holding in stacked relation a plurality of normal lifts and a short base-lift, and means co-operating with said holding means for aligning all of said lifts and for positioning the short base-lift with its breast edge indented from those of the aligned normal lifts.

18. A heel assembling device having, in combination, means for receiving the loosely assembled component lifts of a heel including a short base-lift in stacked relation with their breast edges in alignment, and means for effecting a relative transverse displacement between said short base-lift and the remainder of the lifts to produce a heel hav-

ing the breast edge of its short base-lift indented from those of the aligned normal lifts.

25

19. A heel assembling device having, in combination, clamping members for engaging the end lifts of a heel which comprises a plurality of normal lifts and a short base-lift indented from the breast surface formed by the normal lifts, means for positioning the normal lifts between the clamps to form a flat breast, and separate means for positioning the short lift in its indented relation to the normal lifts.

30

20. A heel assembling device having, in combination, means for clamping the component lifts of a heel including a short base-lift, and means intermediate said clamps for aligning the breast edges of all the lifts except said short lift and for locating said short lift in a position indented from the breast surface thus formed.

35
